UNITED STATES PATENT OFFICE.

LOUIS D. APP, OF SCAPPOOSE, OREGON.

TRACKLAYING MACHINE.

Application filed September 2, 1924. Serial No. 735,490.

To all whom it may concern:

Be it hereby known that I, Louis D. App, a citizen of the United States, and a resident of Scappoose, in the county of Columbia and State of Oregon, have invented a new and useful Tracklaying Machine, of which the following is a specification.

This invention relates to machines for laying track for railroads, logging roads, etc.

10 The primary object of this invention is to provide an exceedingly simple and efficient machine for laying track at a minimum cost.

15 A second object is to deliver ties to the road bed one at a time in a correct position for laying without requiring the workmen to stoop and lift each tie.

A third object is to convey the ties from behind the machine and over-head to the point of delivery.

20 A fourth object is to reduce the maximum distance any tie must be carried to twenty feet from the end of the machine.

A fifth object is to deliver the tie to the men at a distance of about three and one-half feet from the ground, thereby eliminating the loss of time and energy now expended in picking up each tie off from the ground or dragging them out of a pile of ties, as is the case when a number of ties 25 are dropping simultaneously upon the road bed.

A sixth object is to so construct the machine that a large part of the drudgery is removed from the operation of track laying, 30 which renders it possible to engage a higher class of men thereby increasing the speed at which track can be laid, and consequently reducing the cost of track per mile.

A seventh object is to render the machine 35 simple in structure and safe in operation for the men who are working around same.

An eighth object is to permit the machine to operate in either direction so that it does not need to be turned when laying the track 40 or when taking it up.

A ninth object is to so construct the machine that it will deliver steel to the newly laid ties, or pick it up as the case may be, or deliver bridge stringers to some desired 45 point.

A tenth object is to adapt the machine for either main line work or for logging operations by providing storage space on the machine for rails and ties, which will permit 50 supply cars to be switched into place behind the machine while rails and ties are being

taken from or placed in the storage space on the machine.

An eleventh object is to so construct the machine that an internal combustion engine 60 can be employed to furnish the power required.

It will be understood that in order to reduce the amount of manual labor to lay track with my machine that I prefer to deliver the 65 rails and ties in the same position they will occupy in the completed track. The ties are delivered at right angles to the rails at a height which will render lifting unnecessary, and the carrying of the tie is reduced 70 to the minimum. In fact, the tie handling problem is greatly simplified, and it is this item which includes a large portion of the work of track laying.

In order to simplify the illustration I have 75 shown the device as being operated by an internal combustion engine, as far as propelling the vehicle and driving the rail rolls and tie conveyors is concerned, but have shown the conveyor adjustment as being 80 hand-operated which, in most cases, is sufficient.

I accomplish the objects above enumerated as described in the specification following and illustrated in the accompanying drawing, in which:—

Figure 1 is a side elevation showing the machine taking ties from a flat car at its rear end and using steel rails from its own storage space. Figure 2 is a plan of Figure 90 1. Figure 3 is a deck plan showing the storage space for steel and driving rolls and their gearing, above which the decking has been removed to better disclose the parts. Figure 4 is a section taken along the line 95 4—4 in Figure 1. Figure 5 is a side elevation of one end of the machine showing an attachment for taking up rails, which attachment may remain in place all of the time if desired, although not necessarily so. For 100 the sake of clearness this attachment is not illustrated in the first four figures. Figure 6 is a front elevation of a roller hanger shown in Figure 5.

The views are largely diagrammatic, no 105 attempt having been made to show friction clutches, fastenings, etc., which are merely a matter of design and do not enter into my invention.

Similar numbers of reference refer to the 110 same parts throughout the several views.

Referring in detail to the drawing, I have

illustrated the trucks 10 which support the girders 11 and 12 over which I have placed the decking 13 which supports the steel rails 14. Between the girders 12 I have formed a raceway in which are placed the live rolls 15 driven by the bevel gears 16 from the shaft 17, which, in turn, is driven by the internal combustion engine 18.

On the girders 11 are placed the upright 10 posts 19 made rigid by the braces 20 and joined at their upper ends by the stringers 21. Between the longitudinal side rails 22 which are secured to the upper portions of the posts 19 is placed a conveyor 23 to whose 15 ends I have hinged the conveyors 24 and 25 on the frames 26, which are held at the desired elevation by the cables 27 and 28 which pass over the sheaves 29 and are operated by the windlass 30. The conveyors 23, 24 20 and 25 are adapted to carry the ties 31 from the flat car 32 to the new road bed singly in the position they are to occupy instead of dumping them off in bunches or parallel with the steel rails, as is now the common 25 practice.

On the transverse rods 33 I have placed the carriages 34 from which are swung the rail tongs 35 by means of the hoists 36. The tie conveyors 23, 24 and 25 are driven by 30 the chain 37 from the engine 18, which also propels the machine itself along the track being laid through the chain 38, under the control, of course, of the operator through the medium of clutches (not shown) as is 35 the common practice in various types of machines.

To facilitate the taking up of steel rails I have provided a track 39 which is attached to the frame 26 by means of the hangers 40 and 41. The hanger 41 is preferably shorter than the hanger 40 causing the track 39 to slope downwardly toward the machine, as the boom or frame 26 is raised toward a horizontal position or higher. On the track 45 39 I have placed a carriage 42 from which is slung a pair of rail tongs 43.

Near the end of the frames 26 I have attached the slings 44 which support the roller hanger 45 whose roller 46 is adapted 50 to carry a rail 14. In order to better illustrate the use of the attachment I have shown the frame 26 in three positions which I have designated as A, B and C, the two latter being dotted positions.

55 The operation of my device is as follows: When laying track a supply of rails is in place on the decks 13 and a flat car 32 loaded with ties 31 is placed behind the machine. The tie conveyors 23, 24 and 25 are now 60 started by driving the chain 37, and the ties 31 are placed on the conveyors from the car 32 and carried to the road bed where they are received at a convenient height and distributed as needed, during which time the machine is backed away, as required, under

its own power. When enough ties have been laid the rolls 15 are started and a rail 14 is rolled out onto the rolls and fed out of the machine upon the newly placed ties and is then taken care of by the crew.

70 The operation of the device for taking up steel rails, as shown in Figures 5 and 6, is as follows: When the boom or frame 26 is in the lower or "A" position the tongs 43 are attached to the rail 14 which is to be lifted. 75 This point of attachment is slightly forward of the rail center.

When the boom 26 is raised to the position "B" the end of the rail 14 nearest the machine is uppermost, and the entire rail is 80 caused to travel toward the machine. As the rail approaches the position "B" the roller 46 of the hanger 45 is placed under the end of the rail 14 and the boom 26 is then raised toward the position "C", as illustrated. In 85 raising the boom to this position the carriage 42 slides along the track 39 and carries the rail 14 upon the live rolls 15, which, together with the roller 46, now support the rail. The rolls 15 now draw the rail 14 upon the 90 vehicle and finally free the rail tongs 43 and the roller 46 from their load.

In taking up track the operation of the machine itself is reversed by reversing the direction of rotation of the conveyors and 95 rolls. When the tie car is filled, the ties being taken up may be accumulated on the conveyors until an empty flat car can be switched into place, and when the storage space for rails is filled they can be run 100 through onto a waiting flat car. When laying track the rail supply on the machine itself can be renewed in a reverse manner. The hoists 36 are used to pick the rails from the rolls 15 and to place them on the decks 105 13. In placing the rails on the rolls from the decks they may be slid along and rolled down onto the rolls by means of bars.

110 It will be seen that the usual difficulties encountered in track laying, which is the supplying of material to the machines in sufficient quantities, is thereby eliminated, and the machine is therefore adapted to main line work as well as for logging operations where the amount of material required 115 is much less.

In moving the machine great distances, when overhead clearance is limited, the end conveyors can be disconnected and placed upon the conveyor 23 for transportation purposes.

120 I am aware that many forms of track-laying machines have been constructed in the past, I therefore do not claim my device broadly, but I do intend to cover all such 125 forms and modifications as fall fairly within the appended claims.

What I claim as new is:

1. A track-laying machine having, in combination, a flat car having a longitudinal 130

- 5 rail raceway formed in its deck; live rail-carrying rolls in said raceway; gearing for driving said rolls; hoists for lifting rails from said rolls to the deck of said car; a conveyor over said rails adapted to carry ties transversely with said raceway; an extension conveyor hinged to each end of said first mentioned tie conveyor; means for adjusting the height of the swinging ends of said extensions; an internal combustion engine for driving said rolls and conveyors and for propelling said flat car; and having vehicles for supplying rails and ties to the receiving end of said machine.
- 10 2. A device for taking up rails consisting of a vehicle; a boom on said vehicle; a longitudinal track attached to said boom; a rail tong slidably swung from said track; and a roller hanger swung from the end of said boom adapted to slidably support the end of a rail after its opposite end has been lifted upon said vehicle by said tongs.
- 15 3. A device for taking up steel rails consisting of a vehicle; live rolls mounted on said vehicle; a boom swung from said vehicle; a longitudinal track slung under said boom; a carriage on said track; rail tongs supported by said carriage; a roller-carrying hanger supported from the swinging end of said boom adapted to have its roller placed under a rail and support one end thereof while said rail is being drawn upon said vehicle by said live rolls.

LOUIS D. APP.
